CLAIM

The ornamental design for a bird plush with pizza, as shown and described.

DESCRIPTION

FIG. 1 is a front left perspective view of a first embodiment of a bird plush with pizza showing our new design; FIG. 2 is a front elevation view of the first embodiment thereof;

FIG. 3 is a rear elevation view of the first embodiment thereof;

FIG. 4 is a left side elevation view of the first embodiment thereof;

FIG. 5 is a right side elevation view of the first embodiment thereof;

FIG. 6 is a top plan view of the first embodiment thereof;

FIG. 7 is a bottom view of the first embodiment thereof;

FIG. 8 is a front left perspective view of a second embodiment of a bird plush with pizza showing our new design; FIG. 9 is a front elevation view of the second embodiment thereof;

FIG. 10 is a rear elevation view of the second embodiment thereof;

FIG. 11 is a left side elevation view of the second embodiment thereof;

FIG. 12 is a right side elevation view of the second embodiment thereof;

FIG. 13 is a top plan view of the second embodiment thereof;

FIG. 14 is a bottom view of the second embodiment thereof;

FIG. 15 is a front left perspective view of a third embodiment of a bird plush with pizza showing our new design; FIG. 16 is a front elevation view of the third embodiment thereof;

FIG. 17 is a rear elevation view of the third embodiment thereof;

FIG. 18 is a left side elevation view of the third embodiment thereof;

FIG. 19 is a right side elevation view of the third embodiment thereof;

FIG. 20 is a top plan view of the third embodiment thereof; and,

FIG. 21 is a bottom view of the third embodiment thereof. The broken lines depict portions of the article that form no part of the claimed design. The short lines of uneven length represent a plush appearance and are not intended to indicate differences in plush level. FIGS. 15-21 are lined for color. The vertical lines correspond to the USPTO convention for denoting red. The rising horizontal lines correspond to the USPTO convention for denoting brown. The checkered lines correspond to the USPTO convention for denoting yellow.
